UNITED STATES PATENT OFFICE.

PHINEAS G. MACLEAN, OF BOONTON, NEW JERSEY.

DESIGN FOR A VENDING-MACHINE CASE.

SPECIFICATION forming part of Design No. 34,997, dated August 27, 1901.

Application filed July 13, 1901. Serial No. 68,263. Term of patent 7 years.

To all whom it may concern:

Be it known that I, PHINEAS G. MACLEAN, a citizen of the United States, residing at Boonton, in the county of Morris and State 5 of New Jersey, have invented and produced a new and useful Design for a Vending-Machine Case, of which the following is a full, clear, and exact description.

The essential feature of the design resides 10 in the peculiar shape of the case, as illustrated in the accompanying drawings, in which—

Figure 1 is a perspective view. Fig. 2 is a 15 sectional view on the line 2 2 of Fig. 3. Fig. 3 is a vertical longitudinal sectional view.

Referring to the drawings, A indicates the back of the case, which is flat, B the bottom, and C the top, said top having ridges C' and C², and adjacent to the ridge C² the top is

curved, as shown at C³, and continues downwardly, as shown at C⁴. The front of the case D has an inclined ledge D', and beneath the said ledge the said front is formed with an outwardly-projecting portion D² and a flat portion D³, rounded at D⁴, where it joins 25 the bottom B. The sides E are flat and are cut away or curved out at their front edges, as shown at E'.

Having thus fully described my invention, what I claim as new, and desire to secure by 30 Letters Patent, is—

The design for a vending-machine case, substantially as herein shown and described.

PHINEAS G. MACLEAN.
